UNITED STATES PATENT OFFICE

HANS SCHWEITER, OF HOREGEN, NEAR ZURICH, SWITZERLAND

PIRN-WINDING MACHINE

Application filed October 11, 1928, Serial No. 311,876, and in Germany January 9, 1928.

My invention relates to pirl winding machines having an axially to and fro moving winding spindle. With pirls, in particular those intended for so-called automatics, usually a yarn reserve is provided, the object of which is to effect a stoppage of the power loom in due time by the feeler of the loom, that means before the pirl is completely empty. Such a yarn reserve is to be considerably narrower than the main winding. Besides the stationary yarn guide therefore a moving auxiliary yarn guide is arranged which acts only temporarily and is in action at the beginning of the winding operation until the yarn reserve has been established.

In the known designs of pirl winding machines with to and fro moving spindle the auxiliary yarn guide is coupled with the driving gear of the spindle so that it executes the same to and fro motion as the spindle itself. Therefore, as long as the auxiliary yarn guide guides the yarn to be wound up, the latter will always run on the same place of the pirl tube. This results in the fact that the yarn reserve is wound on a very narrow portion of the weft pirl and that it is necessary to adjust the feeler of the loom extraordinarily accurately, to really enable it to stop the loom as soon as the pirl has been unwound up to the reserve. The same drawback exists with machines having a to and fro moving yarn guide and an axially stationary spindle, as in this case the auxiliary yarn guide is stationary too and consequently the yarn runs on also in the described manner.

Now the object of my invention is to obviate this drawback that the known arrangements suffer from, and to so guide the yarn, that the reserve layers become sufficiently wide, so that the feeler of the loom needs not to be adjusted accurately and notwithstanding acts in a satisfying manner.

This object is primarily obtained according to my invention by the fact that the auxiliary yarn guide is designed so as to form a to and fro rocking lever which when in operative position receives its reciprocating motion from the to and fro moving spindle. By suitably determining the position of the fulcrum of the auxiliary yarn guide on the one

hand and of the point of application of the reciprocating spindle on the auxiliary guide on the other hand this arrangement enables to obtain a yarn reserve which, true, is narrower than the main winding, but nevertheless possesses a width such as to warrant a secure co-operation with the feeler of the loom.

The arrangement acts in such a manner, that at the beginning of the winding operation the auxiliary yarn guide is thrown into operation and catches the yarn and so guides it that the yarn reserve is produced on the pirl tube. The auxiliary yarn guide automatically returns to a position of rest after the reserve has been finished, so that the subsequent normal winding operation is executed by the main yarn guide.

In order to permit my invention to be more easily understood, a preferred embodiment of the same is illustrated by way of example in the drawings which accompany and form part of this specification. In these drawings:

Figure 1 is a longitudinal vertical section through the parts in question of my improved pirl winding machine, further, on enlarged scale,

Figure 2 shows the auxiliary yarn guide in elevation,

Figure 3 is a section on line III—III of Figure 2 with the auxiliary yarn guide in its operative position,

Figure 4 is a similar section showing the guide in operative position,

Figure 5 is a detail of the auxiliary yarn guide in a view similar to Figures 3 and 4,

Figure 6 shows a modified form of the auxiliary yarn guide,

Figure 7 is the section on line VII—VII of Figure 6,

Fig. 8 is an end view of one element of the device as shown in Fig. 7, and

Fig. 9 is a side view of the element shown in Fig. 8.

Referring to these figures, 6 denotes the casing in which is mounted the pirl spindle 7 that receives rotary motion from the gear 8 and axial to and fro motion from the grooved disk 9. Two shafts 10 and 11 fixed in the casing 6 have mounted on them the pirl feeler 100

12 that in its turn carries the main yarn guide 13.

In the embodiment illustrated in Figures 1 to 5 an arm 15 is supported by the shafts 10, 5 11 that carries a shaft 14 extending at right angles thereto and having mounted on it an auxiliary yarn guide 16 so as to swing and to be axially shifted thereon. On this guide 16 there is provided a lug 17 which in the operative position, Figure 4, projects into the path 10 of a collar 18 provided on the pirln spindle 7. Consequently the auxiliary yarn guide 16 takes part in the outward motion of the spindle 7, whilst its inward motion is provoked 15 by means of a spring 19, Figure 2.

The yarn guide 16 possesses a sleeve-shaped hub 20 on which is fixed a knob 21. In the latter is lodged a spring 22 abutting on the head of shaft 14 and tending to hold the yarn 20 guide 16 in the inoperative position, Figure 3.

The hub 20 has rotatably mounted on it a sleeve 23 connected to the knob 21 by a coiled spring 24, Figure 3. This spring has a certain initial tension so that it tends to turn the sleeve 23 on the hub 20. In the position of rest of the guide 16, Figure 3, this turning motion is prevented by a ring 25 arranged on the sleeve 23 that may be rigidly connected thereto by a set screw 26. The ring 25 has further an axial groove 27 which is engaged by the upwardly bent head 28 of a rod 29 mounted on the arm 15. A circumferential slot 30, Figure 5, provided in the ring 25 35 enables the operator to alter the position of the latter relatively to the sleeve 23.

In the position of rest the auxiliary yarn guide 16 assumes the position illustrated in Figure 2, in which a nose 31 provided on it abuts on the rod 29. When now the guide 16 40 should be thrown in, an axial pressure is exerted by hand upon the knob 21 whereby the guide 16 is shifted from the position shown in Figure 3 into that of Figure 4, whereby 45 spring 22 is compressed. In this position the nose 31 arrives opposite a recess 35 provided in the rod 29, so that a to and fro rocking motion of the guide 16 is now possible, which motion is provoked by the action of collar 18 50 and spring 19, respectively. In the inward shift of guide 16 the head 28 of the rod 29 leaves the groove 27 of ring 25. The sleeve 23 and the ring 25 connected thereto are thus released and execute a turning motion due to 55 the initial tension of spring 24 until the screw 26 strikes the rod 29. The head 28 of the latter prevents an outward motion of the parts by relaxing of the spring 22, as this head abuts on the outer front face of ring 25 and 60 locks it. The two front faces of the ring 25 are provided with ratchet teeth 32, 33. With the ratchet teeth 32 co-operates the head 28 of the rod 29 and with the ratchet teeth 33 a spring pawl 34 mounted on the guide 16 in 65 such a manner that upon the guide 16 swing-

ing in the one direction the sleeve 23 and ring 25 are taken with it, whilst in the swing motion of guide 16 in the opposite direction the pawl 34 freely glides over the teeth 33, while ring 25 and sleeve 23 are held fast by the head 28 of rod 29 engaging the ratchet teeth 32. 70

A spring 36 arranged between the sleeve 23 and the auxiliary yarn guide 16 assists in producing the described step motion. Now, 75 as soon as the sleeve 23 with the ring 25 has returned to initial position, whereby spring 24 is tensioned, the groove 27 of ring 25 arrives opposite the head 28 of rod 29, so that now under the action of spring 22 the whole system is shifted outward toward the right and again assumes the inoperative position illustrated in Figure 3. Owing to the ring 25 being able to be displaced relatively to sleeve 23 by means of its slot 30, the possibility is 80 given to adjust the period of time during 85 which the yarn guide 16 is in operative position and operation.

As to be seen from Figure 1, the guide 16, when thrown in, catches the yarn that is 90 guided by the stationary main guide 13 to the pirln tube, so that then this latter guide becomes inoperative and the yarn is guided by the auxiliary guide 16. Now, as the distance of the head of guide 16 from the collar 95 18 in the extreme right-hand position of the former is only equal to h^1 , Figure 1, whilst this distance in the extreme left-hand position indicated by dotted lines, of guide 16, is equal to h^2 , the amplitude of the head of 100 guide 16 relatively to the pirln tube is $h^2 - h^1 = h$. Consequently a reserve winding having the width h is produced on the pirln tube, which winding in comparison with the hereinbefore mentioned reserve windings affords the advantage that the individual layers may be wound up in the normal manner and cannot glide off. The distance h is wide 105 enough to secure a satisfying action of the feeler of the loom. 110

When the auxiliary yarn guide 16 thereupon automatically returns to inoperative position, as described above, the further winding operation takes place normally, that means with an amplitude corresponding to 115 the pitch H of the grooved disk 9 until the pirln is finished.

To improve the possibility of adjusting the auxiliary yarn guide 16, so that the position it assumes when at rest and that it returns to 120 after the reserve has been finished can be precisely fixed, I provide the modified form of the guide 16 illustrated in Figures 6 and 7. In Fig. 7 spring pawl 34 is shown 90° away from the showing in Figs. 3, 4 and 5, in order 125 to show more clearly its relationship to the member 25. The other parts exactly correspond to those of the first-described arrangement illustrated in Figures 1 to 5 with the sole exception that the rod 29^a is not rigidly 130

mounted on the arm 15 but has an extension 37 by means of which it is eccentrically fixed on a sleeve 38. The latter is rotatably lodged in a bore of arm 15 and can be fixed in any desired angular position by means of a clamping screw 39. It is this sleeve 38 wherein the shaft 14 is secured and locked by a nut 40. The auxiliary yarn guide 16 is here provided with an adjustable wire eye 16'. The fact that the position of the rod 29^a can be varied at will affords the possibility of fixing the position of the auxiliary yarn guide 16 in the state of rest according to all requirements. The function itself of the auxiliary yarn guide is the same as that of the embodiment described with reference to Figures 1 to 5.

What I claim and desire to secure by Letters Patent, is:—

20 1. In a pirl winding machine an axially reciprocating pirl spindle, a stationary main yarn guide normally adapted to guide a yarn thread and an auxiliary yarn guide adapted to assume an inoperative and an operative position and to assume the guiding control of said yarn in the latter position, and means for imparting reciprocating swing motion from said spindle to said latter guide when in operative position.

30 2. In a pirl winding machine an axially reciprocating pirl spindle, a stationary main yarn guide normally adapted to guide a yarn thread, a journal fixed on a stationary machine part, an auxiliary yarn guide mounted for reciprocating swing motion and for shifting motion on said journal, means for shifting said latter guide on said journal into an inoperative and an operative position, said auxiliary guide being adapted to assume the guiding control of said yarn in the latter position, and means for imparting reciprocating swing motion from said spindle to said latter guide when in operative position.

40 3. In a pirl winding machine an axially reciprocating pirl spindle, a stationary main yarn guide normally adapted to guide a yarn thread, a journal fixed on a stationary machine part, an auxiliary yarn guide mounted for reciprocating swing motion and for shifting motion on said journal, means for shifting said latter guide on said journal into an inoperative and an operative position, said auxiliary guide being adapted to assume the guiding control of said yarn in the latter position, and means for imparting reciprocating swing motion from said spindle to said latter guide when in operative position.

45 3. In a pirl winding machine an axially reciprocating pirl spindle, a stationary main yarn guide normally adapted to guide a yarn thread, a journal fixed on a stationary machine part, an auxiliary yarn guide mounted for reciprocating swing motion and for shifting motion on said journal, means for shifting said latter guide on said journal into an inoperative and an operative position, said auxiliary guide being adapted to assume the guiding control of said yarn in the latter position, a projection on said spindle, a lug on said latter guide adapted to be engaged by said projection upon said spindle moving in one direction and said latter guide being in operative position, and a power accumu-

55 lator attached to said latter guide and adapted to be loaded by said spindle moving it in the engaging direction and to swing said latter guide back while said spindle moves in opposite direction.

60 4. In a pirl winding machine an axially re-

ciprocating pirl spindle, a stationary main yarn guide normally adapted to guide a yarn thread, a journal fixed on a stationary machine part, an auxiliary yarn guide mounted for reciprocating swing motion and for shifting motion on said journal, means for shifting said latter guide on said journal into an inoperative and an operative position, said auxiliary guide being adapted to assume the guiding control of said yarn in the latter position, means for imparting reciprocating swing motion from said spindle to said latter guide when in operative position, and means for automatically shifting it into inoperative position after a certain number of swing motions.

5. In a pirl winding machine an axially reciprocating pirl spindle, a stationary main yarn guide normally adapted to guide a yarn thread, a journal fixed on a stationary machine part, an auxiliary yarn guide mounted for reciprocating swing motion and for shifting motion on said journal, a hub on said latter guide freely rotatable and shiftable on said journal, a spring adapted to be compressed by said hub upon said latter guide being shifted into operative position and to shift the latter into inoperative position when relaxing, said auxiliary guide being adapted to assume the guiding control of said yarn in the operative position, means for imparting reciprocating swing motion from said spindle to said latter guide when in operative position, and means for automatically shifting it into inoperative position after a certain number of swing motions.

6. In a pirl winding machine an axially reciprocating pirl spindle, a stationary main yarn guide normally adapted to guide a yarn thread, a journal fixed on a stationary machine part, an auxiliary yarn guide mounted for reciprocating swing motion and for shifting motion on said journal, a hub on said latter guide freely rotatable and shiftable on said journal, a spring adapted to be compressed by said hub upon said latter guide being shifted into operative position and to shift the latter into inoperative position when relaxing said auxiliary guide being adapted to assume the guiding control of said yarn in the operative position, a projection on said spindle, a lug on said latter guide adapted to be engaged by said projection upon said spindle moving in one direction and said latter guide being in operative position, a power accumulator adapted to be loaded by said spindle moving in the engaging direction and to swing said latter guide back while said spindle moves in opposite direction, and means for automatically causing said spring to shift said latter guide into inoperative position after a certain number of swing motions.

7. In a pirl winding machine an axially reciprocating pirl spindle, a stationary main

- yarn guide normally adapted to guide a yarn thread, a journal fixed on a stationary machine part, an auxiliary yarn guide mounted for reciprocating swing motion and for shifting motion on said journal, a hub on said latter guide freely rotatable and shiftable on said journal, a spring adapted to be compressed by said hub upon said latter guide being shifted into operative position and to 5 shift the latter into inoperative position when relaxing said auxiliary guide being adapted to assume the guiding control of said yarn in the operative position, means for imparting reciprocating swing motion from said spindle to said latter guide when in operative position, a sleeve fixed on said hub, an initially tensioned coiled spring adapted to rotate said sleeve relatively to said hub, means for preventing this rotation of said 10 sleeve in the inoperative position of said latter guide, for releasing it in the operative position of the latter, and for limiting this latter rotation, a pawl and ratchet gear arranged between said latter guide and said sleeve and 15 adapted to cause the latter to stepwise re-tension said coiled spring during the swing motions of said latter guide, and a check pawl and ratchet gear arranged between said sleeve and a fixed part of the machine.
- 20 8. In a pirl winding machine an axially reciprocating pirl spindle, a stationary main yarn guide normally adapted to guide a yarn thread, a journal fixed on a stationary machine part, an auxiliary yarn guide mounted for reciprocating swing motion and for shifting motion on said journal, a hub on said latter guide freely rotatable and shiftable on said journal, a spring adapted to be compressed by said hub upon said latter guide being shifted into operative position and to 25 shift the latter into inoperative position when relaxing said auxiliary guide being adapted to assume the guiding control of said yarn in the operative position, means for imparting reciprocating swing motion from said spindle to said latter guide when in operative position, a sleeve fixed on said hub, an initially tensioned coiled spring adapted to rotate said sleeve relatively to said hub, a longitudinal groove in said sleeve, a fixed bolt engaging said groove when said latter guide is in inoperative position and to release it upon said latter guide being shifted into operative position, a lug on said sleeve, a projection on a fixed machine part adapted to stop said lug after a certain rotation of said sleeve, a pawl and ratchet gear arranged between said latter 30 guide and said sleeve and adapted to cause the latter to stepwise re-tension said coiled spring during the swing motion of said latter guide, a check pawl and ratchet gear arranged between said sleeve and a fixed part of the machine, said latter pawl being formed by said bolt, a nose on said latter guide adapted to abut on said bolt upon the former being in inoperative position, and a recess in said bolt adapted to release said nose when said latter 35 guide is shifted into operative position.
- 40 10. In a pirl winding machine an axially reciprocating pirl spindle, a stationary main yarn guide normally adapted to guide a yarn thread, a journal fixed on a stationary machine part, an auxiliary yarn guide mounted for reciprocating swing motion and for shifting motion on said journal, a hub on said latter guide freely rotatable and shiftable on said journal, a spring adapted to be compressed by said hub upon said latter guide being shifted into operative position and to shift the latter into inoperative position when relaxing said auxiliary guide being adapted to assume the guiding control of said yarn 45 in the operative position, means for imparting reciprocating swing motion from said spindle to said latter guide when in operative position, a sleeve fixed on said hub, an initially tensioned coiled spring adapted to rotate said sleeve relatively to said hub, a longitudinal groove in said sleeve, a fixed bolt engaging said groove when said latter guide is in inoperative position and to release it upon said latter guide being shifted into operative position, means for limiting the rotation of said sleeve upon said latter guide being in operative position, a pawl and ratchet gear arranged between said latter guide and said sleeve and adapted to cause the latter to stepwise re-tension said coiled spring during the 50 swing motion of said latter guide, a check pawl and ratchet gear arranged between said sleeve and a fixed part of the machine, a nose on said latter guide adapted to abut on said bolt upon the former being in inoperative position, and a recess in said bolt adapted to release it upon said latter guide being shifted into operative position, and a recess in said bolt adapted to release it upon said latter guide being shifted into operative position.
- 55 60 65

- erative position, a circumferential angular slot in said sleeve, a headed clamping screw fixed in said hub and extending through said slot, a projection on a fixed machine part adapted to stop the head of said screw, after 5 a certain rotation of said sleeve, a pawl and ratchet gear arranged between said latter guide and said sleeve and adapted to cause the latter to stepwise re-tension said coiled 76 spring during the swing motion of said latter guide, a check pawl and ratchet gear arranged between said sleeve and a fixed part of the machine, said latter pawl being formed by said bolt, a nose on said latter guide adapted 10 to abut on said bolt upon the former being in inoperative position, and a recess in said bolt adapted to release said nose when said latter guide is shifted into operative position. 15
- 20 11. In a pirl winding machine an axially reciprocating pirl spindle, a stationary main yarn guide normally adapted to guide a yarn thread, a journal fixed on a stationary machine part, an auxiliary yarn guide mounted for reciprocating swing motion and for shifting motion on said journal, a hub on said latter guide freely rotatable and shiftable on said journal, a spring adapted to be compressed by said hub upon said latter guide being 25 shifted into operative position and to shift the latter into inoperative position when relaxing, said auxiliary guide being adapted to assume the guiding control of said yarn in the operative position, a projection on said spindle, a lug on said latter guide adapted to be engaged by said projection upon said spindle moving in one direction and said latter guide being in operative position, a power accumulator attached to said latter guide and adapted to be loaded by said 30 spindle moving it in the engaging direction and to swing said latter guide back while said spindle moves in opposite direction, a sleeve fixed on said hub, an initially tensioned coiled spring adapted to rotate said sleeve 35 relatively to said hub, a longitudinal groove in said sleeve, a fixed bolt engaging said groove when said latter guide is in inoperative position, and to release it upon said latter guide being shifted into operative position, 90 a lug on said sleeve, a projection on a fixed machine part adapted to stop said lug after a certain rotation of said sleeve, a pawl and ratchet gear arranged between said latter guide and said sleeve and adapted to cause 40 the latter to stepwise re-tension said coiled spring during the swing motion of said latter guide, a check pawl and ratchet gear arranged between said sleeve and a fixed part of the machine, said latter pawl being formed by said bolt, a nose on said latter guide adapted to abut on said bolt upon the former being in inoperative position, and a recess in said bolt adapted to release said nose when said latter guide is shifted into operative position. 45
- 45 12. In a pirl winding machine an axially reciprocating pirl spindle, a stationary main yarn guide normally adapted to guide a yarn thread, a journal fixed on a stationary machine part, an auxiliary yarn guide mounted for reciprocating swing motion and for shifting motion on said journal, a hub on said latter guide freely rotatable and shiftable on said journal, a spring adapted to be compressed by said hub upon said latter guide being 50 shifted into operative position, means for limiting the rotation of said sleeve upon said latter guide being in operative position, a pawl and ratchet gear arranged between said latter guide and said sleeve and adapted to cause the latter to stepwise re-tension said coiled spring during the swing motion of said latter guide, a check pawl and ratchet gear arranged between said sleeve and a fixed part of the machine, a nose on said latter guide 55 adapted to abut on said bolt upon the former being in inoperative position, and a recess in said bolt adapted to release said nose when said latter guide is shifted into operative position. 60
- 55 13. In a pirl winding machine an axially reciprocating pirl spindle, a stationary main yarn guide normally adapted to guide a yarn thread, a journal fixed on a stationary machine part, an auxiliary yarn guide mounted for reciprocating swing motion and for shifting motion on said journal, a hub on said latter guide freely rotatable and shiftable on said journal, a spring adapted to be compressed by said hub upon said latter guide being 65 shifted into operative position and to shift the latter into inoperative position when relaxing said auxiliary guide being adapted to assume the guiding control of said yarns in the latter position, a projection on said spindle, a lug on said latter guide adapted to be engaged by said projection upon said spindle moving in one direction and said latter guide being in operative position, a power 70 accumulator attached to said latter guide and 75
